UNITED STATES PATENT OFFICE.

CORNELIS ZULVER, OF LONDON, ENGLAND.

LIQUID-FUEL BURNER OR ATOMIZER.

Application filed May 26, 1924. Serial No. 715,970.

To all whom it may concern:

Be it known that I, CORNELIS ZULVER, a subject of the Queen of the Netherlands, of St. Helens Court, Great St. Helens, in the city of London, England, have invented a new and useful Improvement in or Relating to Liquid-Fuel Burners or Atomizers, of which the following is a specification.

This invention relates to oil burners or atomizers and has for its object to provide an improved construction thereof which is particularly adapted for operation by low pressure air although the application of the invention is not to be considered as limited in this respect, as steam, air, or other motive fluid may be employed at any desired pressure. For convenience only air will be referred to.

The improved oil burner or atomizer is characterized in that the air has a high rotative velocity imparted to it in an air supply chamber by means of vanes and is discharged through a contracted or converging conical opening around an oil supply tube provided adjacent to said opening with an annular oil discharge aperture and a diverging deflecting cone which may be surrounded by a cylindrical member or by a flared burner mouth.

As an example the oil supply tube may pass centrally through an air supply chamber which is of relatively large diameter and consists of a rear section of hemispherical form and a forward section of tapered or conical form fitted internally with helical vanes and converging from the larger diameter of the chamber to the outlet which is located around the oil tube just before the oil discharge aperture is reached.

The conical deflector is suitably mounted at the end of the oil supply tube, for example it may be mounted upon the end of a spindle which passes through the rear end of the oil supply tube where the said spindle is provided with a handle and screw threaded gland for the purposes of adjustment in the usual manner.

In a modified construction the conical deflector may be located within or in advance of an enclosing cylindrical member.

Three constructions of oil burners or atomizers carried out in accordance with this invention are illustrated in the accompanying drawings, wherein,

Fig. 1 is a longitudinal section showing one construction.

Fig. 2 is an end elevation of Fig. 1 from the left.

Fig. 3 is a cross section on line X—X of Fig. 1 looking from the left.

Figs. 4 and 5 are respectively a longitudinal section and rear end view of a modified construction.

Fig. 6 is a sectional elevation showing a further modification.

In the construction illustrated in Figs. 1 to 3, an oil supply tube *a* passes centrally through an air chamber *b* of comparatively large diameter, the rear portion or section *b'* of said chamber being of hemispherical form, whilst the forward portion or section *b''* is fitted with internal helical vanes *b''*, and is of coned or tapered formation leading from the larger diameter of the chamber to a somewhat constricted outlet *c* located around the oil supply tube *a* just before reaching the annular oil discharge opening *d*, which is formed between the coned end of the oil supply tube *a* and the face of a diverging deflecting cone *e* carried upon the end of a spindle *f* which passes centrally through the oil supply tube *a* and out of the rear end thereof through a gland *g*.

The contracted discharge aperture *c* of the air chamber *b* opens into an enlarged and somewhat spherical mixing chamber *k* surrounding the deflecting cone *e* and having a contracted discharge opening *k'* which opens into a flared or diverging conical burner mouth or flame tube *l*.

The spindle *f* and gland *g* of the oil tube *a* are provided with screw threads so that the said spindle *f* and the deflecting cone *e* on the end thereof may be adjusted as desired to regulate the size of the opening *d*. A suitable hand wheel *h* is provided on the outer end of the spindle for the purpose of operating the same, and to ensure centralization of the cone *e* projections or supporting members, such as *i*, may be arranged upon the spindle *f*.

The oil tube *a* may be conveniently screwed at its rear end into a body portion *a'* which is made with a suitable extension *a''* adapted to engage and fit into a recess in the stirrup burner holder *j* into which the oil supply inlet *j'* opens.

The said stirrup holder *j* is provided with a screw *j''* for detachably clamping the oil supply tube *a* in place.

The outer casing of the apparatus which constitutes the air chamber *b*, the mixing

chamber *k*, and burner mouth or flame tube *l* may be conveniently constructed as shown in three sections, the first section *b'* which is formed with the air inlet *m* being provided with a socket *n* for the oil tube, whilst the second section is suitably connected to the third section or flame tube *l*, convenient flanges being provided for mounting the said parts upon a plate *o* forming part 10 of the furnace fitment.

The improved burner operates as follows:—Air is admitted through the pipe *m* to the casing *b* surrounding the burner tube *a* which air may be supplied from a fan, 15 compressor or other such suitable source.

Oil is led to the passage *j'* of the stirrup holder *j* from whence it passes into the oil tube *a* and along the same towards the annular oil discharge aperture *d*, the dimensions of which may be regulated by means 20 of the handwheel *h* and spindle *f* to allow the required amount of oil to flow out.

The air having to pass through the helical blades *b'* in the air chamber *b* acquires a 25 high rotative motion and the said chamber being coned towards the outlet end *c* an increased rate of flow occurs at the point where the oil and air meet; this results in the oil being rapidly spun around the 30 conical deflector *e* at the end of the spindle *f* and finally atomized and intermixed with the air current within the mixing chamber *k*.

This mixing chamber *k* as will be seen, 35 is of restricted formation, which ensures a further intimate mixing of the oil and sprays before being finally emitted from the conical burner mouth or flame tube *l* where it may be ignited by means of a common torch.

40 In the modified construction shown in Figures 4 and 5 the operation and construction is similar to that shown in Figs. 1 to 3 except that the air inlet *m* is led into the side of the air chamber *b* above the 45 level of the lower edge of the outlet *c* so that the lower part of the air chamber forms a pocket or well below the dotted line *x* adjusted to receive and hold any oil which may by any mischance pass into the 50 air chamber *b* instead of going into the furnace, and the oil thus received in the said pocket will be held therein instead of flowing down the air inlet branch into the fan as might be the case when the air supply enters the bottom of the air chamber.

55 These Figures 3 and 4 also show the air inlet branch fitted with a thermometer *y* for ascertaining the temperature of the air being admitted and a suitable damper *g*, such as indicated in dotted lines in Fig. 5 60 may also be provided for controlling the air supply. *r* is a flame tube provided with perforations *r'*.

In the construction shown in Fig. 6, the 65 mixing chamber is dispensed with and the

annular oil discharge aperture and the diverging deflecting cone onto which it opens are located a short distance beyond the termination of the coned or tapered outlet from the air supply chamber, which chamber is fitted with internal vanes as before.

In this modified construction *a* is the oil supply tubes passing centrally through an air supply chamber *b* fitted with internal helical blades *b'* and coned or tapered at 75 its forward end to form a somewhat restricted outlet *c* located around the oil supply tube *a* just before reaching the annular oil discharge opening *d* which is formed between the internally coned end of the oil supply tube *a* and the face of a diverging deflecting cone *e* carried upon the end of a spindle *f* which passes centrally through the oil supply tube *a* and out of the rear end thereof through a gland *g*, where it 80 is provided with an adjusting handle *h*.

The contracted conical discharge aperture *c* of the air chamber is enclosed by a cylindrical member *s* which is provided with an internally bevelled edge and terminates just beyond said air discharge aperture *c*, as shown, or approximately coincident therewith, and the said cylindrical member *s* may be carried back around the air chamber *b* as shewn so as to carry the 90 same, the rear end of said cylindrical member being conveniently provided with a flange *t* serving as a means for attaching the burner as a whole to the furnace door or supporting plate *o*.

The oil supply aperture *d* is located approximately coincident with the end of the cylindrical member *s* and the deflecting cone *e* projects slightly beyond the same.

In operation the air in passing through the helical blades in the air chamber *b* acquires a high rotative motion and the said chamber being coned or tapered towards the outlet end an increased rate of flow occurs at the outlet *c* where the oil and air meet, this results in the oil being rapidly spun around the conical deflector *e* at the end of the spindle *f* and discharged as a finely atomized spray intimately mixed with air so as to be readily ignited by means of a common torch.

The spindle *f* is fitted with a hand-wheel *h* and is screwed into the gland *g* so that by operating the said hand wheel *h* the dimensions of the oil discharge aperture may be regulated to allow the required amount of oil to flow out.

What I claim as my invention and desire to secure by Letters Patent is:—

1. The improved oil burner or atomizer 125 comprising the combination of an oil supply tube terminating in an annular oil discharge opening, a cone-shaped deflector mounted adjacent said annular oil discharge opening and extending outwardly there- 130

from, an air supply nozzle mounted about said oil tube and adapted to direct the movement of air against the outer end of said oil supply tube and against said deflector whereby to atomize the oil and project the same outwardly from said deflector, a mixing chamber secured to said air nozzle, and a flame tube extending outwardly from said mixing chamber.

10 2. The improved oil burner comprising an oil supply tube having an annular oil discharge opening at the outer end thereof, a cone-shaped deflector positioned in spaced relation to said annular oil discharge opening, an air pressure chamber mounted about said oil tube, vanes mounted upon the inner walls of said air pressure chamber and adapted to rotate the air about said oil tube and toward the outer end thereof, an outer 15 mixing chamber and a flame tube extending outwardly from said mixing chamber.

20 3. The improved oil burner or atomizer comprising an oil supply tube having an annular oil discharge opening at the outer end thereof, a diverging cone-shaped deflector positioned in spaced relation to said annular oil discharge opening, a converging air supply chamber mounted about said oil supply tube, a plurality of vanes mounted upon the 25 inner converging walls of said air supply

chamber whereby to impart a high rotative velocity to the air passing through said chamber, said converging walls being adapted to direct the air against the outer end of said oil tube and against said deflector whereby to atomize the oil, an outer mixing chamber, and a flame tube extending outwardly from said mixing chamber.

4. The improved oil burner or atomizer comprising the combination of an oil supply pipe, a convergent air chamber surrounding said pipe, helical vanes mounted upon the inner walls of said air chamber and adapted to rotate the air within said air chamber as it moves toward the convergent end thereof, said supply pipe at its outer end extending outwardly from the convergent end of said air chamber, a mixing chamber secured to the convergent end of said air chamber and extending outwardly 45 therefrom, said mixing chamber being substantially larger than said convergent end of said air chamber, and a divergent deflecting cone mounted within said mixing chamber and partially extending into the outer 50 end of said pipe, said deflecting cone being adapted to deflect the oil and air into said mixing chamber whereby to atomize the oil.

CORNELIS ZULVER.
